UNITED STATES PATENT OFFICE.

LAWRENCE YOSCO, OF NEW YORK, N. Y.

BANJO-RESONATOR.

1,289,999.

Specification of Letters Patent. Patented Dec. 31, 1918.

Application filed November 21, 1917. Serial No. 203,106.

To all whom it may concern:

Be it known that I, LAWRENCE Yosco, a citizen of the United States, and a resident of the city of New York, borough of Manhattan, in the county and State of New York, have invented a new and Improved Banjo-Resonator, of which the following is a full, clear, and exact description.

This invention relates to musical instruments and particularly to banjos, and has for an object the provision of an improved construction which will cause the banjo to have a clear tone in rainy or wet weather as well as in dry weather.

Another object of the invention is to provide a banjo with a resonator formed with compartments and a pair of rings so constructed and arranged as to provide spaced supports for the head.

A further object of the invention is to provide a banjo with means for forming different compartments and thereby producing better carrying qualities.

A still further object of the invention is to improve the construction of a banjo or similar instrument so as to increase the volume and improve the quality of tone as well as make it a dependable instrument in all kinds of weather for all sizes and types.

In the accompanying drawing:

Figure 1 is a top plan view of the banjo disclosing an embodiment of the invention.

Fig. 2 is a bottom plan view of the structure shown in Fig. 1, certain parts being broken away for better illustrating the structure.

Fig. 3 is a section through Fig. 1 on line 3--3, same being on an enlarged scale.

Fig. 4 is a sectional view through Fig. 1 on line 4--4, same being on an enlarged scale.

Fig. 5 is a detail fragmentary view similar to Fig. 3, but disclosing a slightly modified construction.

Referring to the accompanying drawing by numerals, 1 indicates the resonator of the banjo and 2 the neck which is of substantially usual construction with the exception of a slight difference shown in Fig. 3, namely the arrangement of the downwardly extending portion 3 having a notch for accommodating the head 4 of a clamping screw 5. Screw 5 passes through the lower part of the resonator 1 and is held in place by one or more nuts 6. The screw 7 passes through the head or eyelet member 4 of the screw

5 so that when the nuts 6 are tightened the section 3 will be clamped tightly against the resonator 1. This fastening means is in addition to the usual extension 8 and 60 clamping screw 9.

The resonator 1 is formed with an outer wall 10 of any desired material, as for instance laminated wood, said outer wall carrying the usual ring 11 held in place by pins 12 and normally raised slightly by the projections 13 which may be the heads of metallic tacks. Spaced inwardly from the wall 10 is an inner wall or ring 14 of any desired material, as for instance laminated wood, 70 said wall being preferably of the same height as the outer wall, but of similar diameter. A bottom member 15 of wood or other similar material is glued or rigidly secured to the walls 10 and 14 as shown in Fig. 4 whereby an annular chamber 16 is provided, which chamber is divided into a plurality of sections by a number of spaced blocks 17, said blocks being formed of wood. Preferably there are provided four of these blocks, 80 though a greater or less number could be used without departing from the spirit of the invention, said blocks being secured to both the outer and inner wall, by glue or any other desired matter. Inner wall 14 85 is provided with a number of apertures 18 through which a wrench or key is passed when tightening up screws 19. Arranged on top of the inner wall 14 is a ring 20 of metal or other desired material, said 90 ring being preferably of greater diameter than ring 11 whereby the center part of the skin 21 is slightly raised. In addition to these parts the usual strings, bridge and other members found in an ordinary banjo 95 are provided and connected in the usual manner.

In banjos and in any other instrument using a skin for a diaphragm it has been found that the weather affects the tone and carrying quality of the sound to a large extent. For instance, in wet weather an ordinary banjo or drum will not give the proper sound nor will the sound carry a considerable distance. To overcome this objection inner wall 14 is provided whereby the distances between the supports for the skin 21 are reduced and the head is properly maintained taut and supported for producing a clear sound even when the weather 110 conditions are objectionable, as for instance during rain. In small banjos the difficulty

above mentioned is not present to any considerable extent, but is very noticeable in large banjos. By reducing the distance between the supporting rings the effect of the small banjo is secured while the volume of sound of the large instrument is maintained. In addition the chamber 16 assists in causing the sound to carry.

In Fig. 4 will be seen a slightly modified form of the invention in which the inner wall 14' extends above wall 10, the upper end of said section being rounded so as to properly support the head 21. In this form of the invention wall 14' is also solid throughout as the apertures 18 are dispensed with. The apertures 18 in the preferred form could be dispensed with provided some other fastening means could be used other than the screw 19.

It will be noted that the construction of an inner rim, outer rim and a bottom produces a resonating chamber and that the inner rim is higher than the outer rim so as to hold up and support the head or skin and prevent it from sagging and sinking down in the center from the pressure of strings acting on the bridge either during fair weather or rainy weather.

What I claim is:

1. A banjo resonator comprising an outer circular wall, an inner circular wall spaced from the outer wall, spaced solid connecting members arranged between said walls and rigidly secured to the respective walls, said connecting members acting as division walls,

and a bottom member connected to said inner and outer walls at their lower edges and to the lower edges of said connecting members whereby a plurality of chambers are provided between said walls.

2. A banjo resonator comprising an outer wall, an inner wall spaced from the outer wall, a bottom member connecting said walls, means on the inner wall extending above the outer wall so that the head used on the resonator will be supported directly on the inner wall as well as the outer wall.

3. A banjo resonator comprising a pair of spaced walls, a solid bottom connecting the walls at their lower edges, the inner wall being higher than the outer wall, and solid blocks connected to said bottom and to said walls for dividing the spaces between the walls into compartments, and means on the outer edge of each of said walls for engaging the head of the resonator.

4. A banjo resonator comprising an outer wall, an inner wall spaced from the outer wall, a solid bottom connecting said walls at the lower part thereof, a pair of rings arranged one on the upper edge of each of said walls, the ring on the inner wall being of such size as to cause the height of the inner wall to be greater than the height of the outer wall, and wooden partitions connected to said walls and to said bottom for dividing the space between the walls into compartments.

LAWRENCE YOSCO.
